PUMP AND PUMPING SYSTEM.
APPLICATION FILED SEPT. 20, 1915.

Patented Jan. 15, 1918:

3 SHEETS—SHEET 3.

Fig. 3.

UNITED STATES PATENT OFFICE.

BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

PUMP AND PUMPING SYSTEM.

1,253,558.

Specification of Letters Patent. Patented Jan. 15, 1918.

Application filed September 20, 1915. Serial No. 51,524.

To all whom it may concern:

Be it known that I, BURTON S. AIKMAN, a citizen of the United States, residing at Milwaukee, in the county of Milwaukee and 5 State of Wisconsin, have invented a certain new and useful Improvement in Pumps and Pumping Systems, of which the following is a full, clear, concise, and exact description, reference being had to the accompanying drawings, forming a part of this specification.

My invention relates to pumps and pumping systems and contemplates an improved apparatus which may be employed as an 15 isolated plant for furnishing water to a residence or an industrial establishment from a nearby source, such as a well.

It is the purpose of my invention to provide an improved system which supplies 20 water "fresh from the well", that is, without the intervention of a storage or reserve tank, and which will be under "faucet control", by which I mean that the flow of water is controlled by the acts of opening and 25 closing the faucets which form the supply-outlets of the system.

To supply water fresh from the well and to maintain the flow of water under faucet control is a matter of prior art. The apparatus and systems heretofore known and used were, however, subject to inherent difficulties due to the fact that their mode of operation required complexities such as alternately-operating chambers, valves operating 30 by marginal differences in pressure, and due to the fact that the pneumatic control employed led to frequent misoperations, such as are commonly called "blowovers", where the system becomes cleared of 35 water and the compressed air employed as an operating medium is wasted.

According to my invention there is provided a single water-chamber alternately subject to air-pressure and relieved therefrom, the alternations being secured by the 45 actuations of valve mechanisms, which, in turn, are dependent, on the one hand, directly and mechanically upon the fall of the water in the chamber, and on the other hand upon a positively-operating time-element device.

It will be understood that the system is constantly under pressure, and it is, therefore, a further object of my invention to 55 provide an apparatus which will be as free

from leaks as possible, which operates with a minimum consumption of air, and which operates reliably and positively.

Notwithstanding the gradual rise and fall of the water in the chamber, I provide 60 means for suddenly actuating the valve mechanism, an especially desirable feature.

My invention is illustrated in the accompanying drawings, in which:

Figure 1 is a more or less diagrammatic 65 view illustrating the system as a whole;

Fig. 2 is a plan view of the pump;

Fig. 3 is a vertical axial sectional view taken on the plane of the line 3—3 of Fig. 2 and looking in the direction indicated by 70 the arrows;

Fig. 4 is a vertical axial sectional view taken on the plane of line 4—4 of Fig. 3 and looking in the direction indicated by 75 the arrows; and

Fig. 5 is a partial sectional view taken on the plane of the line 5—5 of Fig. 2 and looking in the direction indicated by the arrows, Figs. 2 and 5 being drawn on a larger scale than Figs. 3 and 4.

Referring first to Fig. 1, which, as before stated, is diagrammatic, it will be seen that the well curbing is illustrated at 8, the water-level being indicated at 9. The pump structure, which I have indicated broadly 85 by the reference character 10, is disposed in the well at a suitable distance below the water-level therein, as will be described.

The pump structure has leading therefrom three pipes, an air-pressure pipe 11, an 90 exhaust-pipe 12 and a water-discharge pipe 13. The air-pressure pipe 11 is connected with a compressed-air tank 14, in which air is compressed by means of a compressor 15, operated, for instance, by an electric motor 16. It will be clear to those skilled in the art that the compressor 15 may be operated by any suitable means, such as a gas-engine or steam-engine, and, if desired, means may be provided for automatically 100 starting and stopping the prime mover dependent upon the fall and rise of pressure in the tank 14. In the pipe 11 the cut-off valve 11^a, air strainer 11^b, reducing valve 11^c, gage 11^d and drain cock 11^e are provided.

The water-discharge pipe 13 leads to various branch pipes 17 and 18, each of which in turn leads to an outlet-faucet 19. By means of a pipe 20 the discharge pipe 13 is 110

connected with a chamber 21, closed except for the entry-pipe 20, for a purpose which will be pointed out presently.

It will now be understood that this system represents an isolated plant for installation in a residence, for instance. The water-discharge pipe leads from the well conveniently nearby, to the distribution-pipe in the building, and the compressor, motor, compressed-air tank and chamber are suitably housed in any convenient way.

As before pointed out, air-pressure is constantly maintained upon the system. It is therefore necessary to maintain a certain pressure between predetermined minimum and maximum limits in the compressed-air tank 14, this being done by the proper starting and stopping of the compressor 15, either manually or automatically. It has been my experience that, a proper compressed-air tank being provided, it is necessary in employing a distribution system for an ordinary residence, for instance, merely to operate the compressor intermittently, say every two or three days, for a short time, in order to keep the pressure in the compressed-air tank within the desired limits.

It will appear as this description proceeds that with the pressure properly maintained upon the system, everything is at rest so long as all the outlet-faucets of the system are closed, but as soon as one of them is opened the pumping mechanism will operate to maintain continuous the flow which immediately commences. When the faucet is again closed the apparatus comes to rest and it will appear that the feed has been direct from the well with the proper pressure to distribute it to whatever points desired.

I refer now to Figs. 2 to 5, inclusive, to describe the pumping mechanism. A head-member 22 and a primary base-member 23, both of circular form, are joined by a cylindrical housing 24, which forms a water-chamber 25. As illustrated in Fig. 4, the head-member 22 and the primary base-member 23 are tied together by means of two pipes 26, 26, which thread into the head-member 22 and pass through openings in the primary base-member 23, the lower ends of these pipes being screw-threaded for the reception of nuts 27 which, when tightened, clamp the housing 24 firmly in place to form a watertight and airtight compartment. Secured to the under side of the primary base-member 23, by means of screws 28, 28, is the secondary base-member 29, which has extending downwardly therefrom a central boss 30 to which a nut 31 is screw-threaded, a conical screen 32 being clamped between the nut 31 and the boss 30 and thus held against the under side of the secondary base-member 29. The secondary

base-member 29 is provided with two water-inlet openings 33, 33, each of which is controlled by a lift-valve 34, normally held seated by means of springs 35, 35, disposed between the respective valves and the primary base-member 23.

The primary base-member 23 is provided with an axial opening 37, which is surrounded by an upwardly-extending boss 38, a cylinder 39 being supported upon and extending upwardly from said boss, as clearly shown in Figs. 3 and 4. The top of the boss 38 forms a valve-seat 40, and this valve-seat is adapted to be engaged by the ball float-valve 42, which is confined within the cylinder 39. As shown in Fig. 3, the top of the cylinder 39 is closed for the proper retention of the ball float-valve 42. The cylinder 39 is provided with elongated vertical slots 43, through which the water may pass inwardly and outwardly, as will be described. Entrance of water into the chamber 24 is thus provided through the screen 32, openings 33, 33, opening 37, and slots 43, 43. The exit of water from the chamber 24 is provided for through the slots 43, 43, the opening 37, the passageways 44, 44, formed by the spider construction of the top of the nuts 27, 27, and the pipes 26, 26, the further course of the water being later described.

The head-member 22 is provided with an atmosphere passageway 47, the compressed-air-inlet passageways 48 and 49, the primary water-chambers 50, 50, and the secondary water-chamber 51. These passageways and chambers are isolated from each other, as will be described, the atmosphere passageway being connected with the pipe 12, the compressed-air-inlet passageway 48 being connected with the pipe 11, and the secondary water-chamber 51 being connected with the discharge-pipe 13.

Referring first to the atmosphere-inlet passageway 47, it will be seen that it is so fashioned as to lead to the axial opening 52 in the bottom of the head 22, a valve-seat 53 surrounding this opening.

Supported from the under side of the head 22 is an annulus 54, disposed coaxially with the cylinder 24. This annulus forms a water chamber and supports a diaphragm-chamber structure which will now be described. This structure is composed of two primary parts 55 and 56, the former being mounted in and closing the bottom of the annulus 54 and the latter being secured to the under side of the former with the diaphragm 57 clamped between the two. Thus, the diaphragm has on its upper side the diaphragm-chamber 58, and on its lower side the diaphragm-chamber 59. The central portion of the diaphragm 57 is clamped between a plate 60 and a cup-member 61 by means of a screw 62. This cup-member is

guided, by means of ribs 63, 63 in the rim 64 of the diaphragm-chamber part 55.

A valve-stem 65 is screwed into a guide-block 66, which, as illustrated in Fig. 3, is mounted for reciprocation in a sleeve 67, disposed axially in the opening 52. A valve 68, double-faced so that it acts as a valve on both sides, is clamped upon the valve-stem 65 between the block 66 and a collar 69. The upper valve-face co-operates with the valve-seat 53, and the lower face co-operates with the valve-seat 70 formed at the top of the rim 64, as will be described presently.

Mounted so as to be engaged by the block 66 is a valve-stem 71, which passes through an axial opening 72, which connects the compressed-air passageways 48 and 49. A valve-seat 73 surrounds the passageway 72, and a valve 74, carried upon the stem 71, co-operates with this valve-seat. The valve 74 is guided in a central opening 75 at the top of the head-member 22, which opening is closed by a plug 76, between which and the valve a spring 77 is disposed.

The lower end of the stem 65 extends downwardly into the cup-member 61, wherein it is provided with a head 78, adapted to be engaged by the bottom of the cup-member, as illustrated in Fig. 3. This cup-member is made in the form of a spider, in order to permit of the insertion of this head-member. A spring 79 is disposed between a collar on the head-member and the under side of the top of the cup-member.

The bottom of the diaphragm-chamber 59 is closed by a partition 80, between which and the under side of the diaphragm 57 a spring 81 is disposed. An opening 82 is provided centrally in the partition 80, this opening being controlled by a valve 83, carried upon a stem 84, guided by means of ribs 85 in the opening 82. As will be described, the top of the stem 84 is adapted to be engaged by the screw 62, in the downward movement of the diaphragm, to open the valve 83 against the tension of the spring 86. The chamber 87 below the partition 80 is connected by means of a small passageway 88 with the atmosphere passageway 47.

The upper diaphragm-chamber 58 is provided with a restricted outlet 89, which affords a time element in the return of the diaphragm 57 from its lower to its upper position, the interval thus provided for being utilized for the refilling of the pump.

The operation of my pump and system is as follows: In the condition shown in Figs. 3 and 4 the apparatus has just reached a point where the consignment of water in the chamber 24 has been driven therefrom by the action of compressed air entering by way of the passageways 48, 72 and 49. The water has reached its lower level, as illustrated, and the ball float-valve 42 has been seated upon the seat 40. As soon as this

ball float-valve has been seated the continued application of the compressed air is effective upon the upper side of the diaphragm 57 by way of the space between the cup-member 61 and the rim 64. Previous to this, that is during the time that water was being forced out of the chamber 24, through the central opening 37 and upwardly through the pipes 26, 26, the air-pressure was not effective in its action upon the top of the diaphragm 57 for the reason that the pressure is also transmitted to the under side of the diaphragm by way of the passageway 90 leading from the diaphragm-chamber 59 to one of the chambers 50.

It will be obvious that while the expulsion operation is going on the water in the chambers 50 is under the pressure of the compressed air, and, since that pressure is transmitted to the under side of the diaphragm 57 by means of the passageway 90, the diaphragm will be balanced so far as effective air-pressures are concerned and will be retained in its uppermost position by means of the spring 81. When, however, the action reaches the point illustrated in Figs. 3 and 4, the pressure of the motive fluid on the under side of the diaphragm 57 is cut off by the valve 42 and the pressure on the upper side of the diaphragm builds up until it easily overcomes the tension of the spring 81 and the pressure of the water in chamber 50. This moves the diaphragm 57 toward its lowermost position compressing the spring 79. Finally the spring overcomes the pressure holding valve 68 on its seat and suddenly expands. In this downward movement of the diaphragm three changes occur. The valve 74 is brought down on the seat 73, and the valve 68 is brought down on the seat 70, because of the engagement of the top of the head 78 with the under side of the top of the cup-member 61, and the valve 83 is moved to its open position by reason of the engagement of the screw 62 with the top of the stem 84. This action closes off the compressed air to the water-chamber 25 and opens the water-chamber to the atmosphere. At the same time the under side of the diaphragm 57 is exposed to the atmosphere for exhaust. When these conditions are assumed the chamber 25 immediately commences to fill, check-valves 34, 34, opening under the head of water in the well, and this action continues until the valves are again reversed. I provide for this refilling period as follows: It will be seen that, as soon as the valves have been thrown in their lowermost position, the diaphragm 57 will immediately begin to rise under the influence of the spring 81. It is retarded in resuming this position, however, because the water in the diaphragm-chamber 58 must all find its way out through the restricted passageway 89, since the large passageway 130

100

105

110

115

120

125

between the cup-member 61 and the rim 64 has been closed by the valve 68. The nature of the connection between the valve-stem 65 and the cup-member 61, as has been described, permits of a considerable upward movement of the diaphragm 57 before the bottom of the cup-member engages the bottom of the head 78 to raise the stem. The duration of this upward movement prior to the raising of the stem 65 is dependent upon the size of the opening 89, and I am therefore enabled to provide whatever time is necessary for refilling, dependent upon conditions.

15 It has been my experience that, with a structure built substantially along the lines of that illustrated in the drawings, and substantially of those proportions, submerged a few feet below the level of the water in 20 the well, a period of about 1.5 seconds is required for the filling operation, and I therefore regulate the size of the aperture 89 to permit of a period of that time for the upward movement of the diaphragm 57 before 25 the head 78 is engaged by the bottom of the cup-member 61 to throw the valves in their upward position.

It is pertinent here to point out that the stem 84 of the valve 83 is not engaged until 30 after the diaphragm 57 has made a considerable downward movement and, conversely, is released after a small portion of the upward movement of the diaphragm has been accomplished. The downward movement of the diaphragm and the opening of 35 the valve 83 releases the water confined there, and in the upward movement of the diaphragm the valve closes, under the following tension of the spring 86, to retain 40 the water above it.

It may be assumed that in this refilling operation which has been described the water reaches the level indicated by the dot-and-dash line, at which time the valves are 45 reversed so as to close the chamber 25 to the atmosphere and open it to the compressed air.

It will be kept in mind that in the refilling operation the float-valve 42 rises with 50 the entering water and goes to the top of the cylinder 39, where it remains until the level of the water has been lowered to a point where it may take the ball valve down with it again. The continued application of the 55 compressed air now forces out the water in the chamber 25, the water passing through the opening 37, the openings 44, 44, the pipes 26, 26, the chambers 50, 50, and thence through the openings 91, 91, past the check- 60 valves 92, 92, and into the secondary water-chamber 51, these check-valves being held on their seats under normal conditions by means of the springs 93, 93, disposed between the valves and the plugs 94, 94.

65 From the chamber 51 the water passes to

the distribution system by way of the pipe 13. This operation then continues until the float-valve 42 is brought down to the seat 40, whereupon the valves are reversed and the operation hereinbefore described is repeated. 70

It is assumed, of course, that this operation which has been described takes place only when there is a withdrawal of water from the system. If all the outlets of the distribution system are closed, everything 75 will be at rest since, although there is pressure on the top of the water in the chamber 25, there is no outlet for the water. When the water is forced out through the discharge-pipe 13 it will be seen that, in addition to going to the distribution pipes 17 and 18, the water will also be forced into the air-chamber 21, confining an air-cushion above the water-level formed therein, as indicated in dotted lines. 80

85 The speed with which the water-chamber fills to the upper level of course depends upon the sizes of the inlet passageways and the head of the water in the well. As before indicated, with a structure as shown, 90 the time is about 1.5 seconds. If the capacity of the discharge and distribution-pipes is great enough this momentary cessation of pressure will be hardly perceptible at the faucets, particularly since the expulsion 95 period, assuming one or more faucets to be open for a considerable length of time, consumes practically all of the time. However, in order that the gap in the flow may be properly filled in, I provide the air-chamber 21, to which the part 20 delivers from the discharge-pipe 13. Obviously, when the water in the discharge-pipe 13 is under pressure, as it is practically all of the time, a 100 certain amount of water is forced up into the chamber 21. This action compresses the air in the chamber and forms a cushion, which is maintained so long as the pressure is not relieved. As soon as the pressure is relieved, 105 however, by the cessation of pressure in the pump with a faucet open, the air is given opportunity to expand and in doing so forces out the water which has become packed 110 therein and provides a flow from the faucet during the refilling period of the pump. 115 This chamber 21 will, of course, be distinguished from a storage-tank, since all it does is to increase the capacity of the system and provide means for a certain amount of compression to be released for a very short 120 period, about 1.5 seconds, at a time.

110 It will be understood that this water which is in the chamber 21 is directly a part of the discharge system, being located in effect directly between the well and the 125 faucet, and the small consignment of water is constantly being changed. In this way a continuous flow from the faucets is insured.

I have found by experiment that the air in the chamber 21 is kept properly replen- 130

ished by bubbles of air which follow the expulsion of water from the water-chamber 25 of the pump structure; and that it is automatically relieved from an excess of air by 5 the opening of a faucet, this latter action being instantaneous and imperceptible to the opening of the faucet.

It will be seen that the lower level of the water in the water-chamber positively determines the reversal of the valves, and that the upper level of the water is determined by a positively and uniformly-operating time element. In this way reliable operation is secured and the desirable sudden action of 15 the valve at the end of a refilling or emptying operation is effectively obtained. Suction may be applied on the pipe 12, if desired. Certain of the broad features of the present invention are disclosed and claimed 20 in my prior copending application Serial No. 50,941, filed Sept. 16th 1915.

I have endeavored to embody the features of my invention in a simple structure involving a minimum number of parts of simple design, and some of the more limited 25 of the appended claims are directed to these more specific features.

I claim:

1. In a pump, a water-chamber, an auxiliary chamber having inlet and outlet valves said auxiliary chamber being connected with said water-chamber, an exhaust-port for said water-chamber, a compressed-air port for said water-chamber, valves for 30 said ports, pressure-means for operating said valves, one side of said pressure-means being exposed to the pressure in said auxiliary chamber to close the exhaust port and open the compressed air port, and the other side being exposed to the pressure in said 35 water-chamber to open the exhaust port and close the compressed air port, and a valve for controlling the connections between said chambers.

2. In a pump, a water-chamber, an auxiliary chamber having inlet and outlet valves said auxiliary chamber being connected with said water-chamber, at the bottom of the latter, an exhaust port for said 40 water-chamber, a compressed-air port for said water-chamber, valves for said ports, pressure-means for operating said valves, one side of said pressure-means being exposed to the pressure in said auxiliary 45 chamber to close the exhaust port and open the compressed air port, and the other side being exposed to the pressure in said water-chamber to open the exhaust port and close the compressed air port, and a float valve 50 for controlling the connections between said chambers.

3. In a pump, a water-chamber, an auxiliary chamber having inlet and outlet valves said auxiliary chamber being connected with said water-chamber, an exhaust-

port for said water-chamber, a compressed-air port for said water-chamber, valves for said ports, pressure-means for operating said valves, one side of said pressure-means being exposed to the pressure in said auxiliary chamber, and the other side being exposed to the pressure in said water-chamber, a valve for controlling the connections between said chambers, and a valve for controlling the application of the pressure in 70 said water-chamber to said pressure-means.

4. In a pump, a water-chamber, an auxiliary chamber having inlet and outlet valves said auxiliary chamber being connected with said water-chamber, an exhaust-port for said water-chamber, a compressed-air port for said water-chamber, valves for said ports, pressure-means for operating said valves, one side of said pressure-means being exposed to the pressure in said auxiliary chamber, and the other side being exposed to the pressure in said water-chamber, a valve for controlling the connections between said chambers, a valve for controlling the application of the pressure in 75 said water-chamber to said pressure-means.

5. In a pump, a water-chamber, an auxiliary chamber having inlet and outlet valves said auxiliary chamber being connected with said water-chamber, an exhaust-port for said water-chamber, a compressed-air port for said water-chamber, pressure-means connected on one side with the auxiliary chamber, and on the other side connected with the interior of the water-chamber by a main and a restricted passageway, a valve structure operated by said pressure-means and controlling said exhaust and compressed-air ports and said main passageway.

6. In a pump, a water-chamber, an auxiliary chamber having inlet and outlet valves said auxiliary chamber being connected with said water-chamber, an exhaust-port for said water-chamber, a compressed-air port for said water-chamber, pressure-means connected on one side with the auxiliary chamber, and on the other side connected with the interior of the water-chamber by a main and a restricted passageway, 95 a valve structure operated by said pressure-means and controlling said exhaust and compressed-air ports and said main passageway, 100 a valve structure operated by said pressure-means and controlling said exhaust and compressed-air ports and said main passageway.

7. In a pump, a water-chamber, an auxiliary chamber having inlet and outlet valves said auxiliary chamber being connected with said water-chamber, an exhaust-port for said water-chamber, a compressed-air port for said water-chamber, pressure-means connected on one side with the auxiliary chamber, and on the other side connected with the interior of the water-chamber by a main and a restricted passageway, 110 a valve structure operated by said pressure-means and controlling said exhaust and compressed-air ports and said main passageway, 115 and an exhaust relief passage from the first side of said pressure-means.

8. In a pump, a water-chamber, an auxiliary chamber having inlet and outlet valves said auxiliary chamber being connected with said water-chamber, an exhaust-port for said water-chamber, a compressed-air port for said water-chamber, pressure-means connected on one side with the auxiliary chamber, and on the other side connected with the interior of the water-chamber by a main and 120 a restricted passageway, a valve structure operated by said pressure-means and controlling said exhaust and compressed-air ports and said main passageway, 125 and an exhaust relief passage from the first side of said pressure-means.

6
a restricted passageway, a valve structure operated by said pressure-means and controlling said exhaust and compressed-air ports and said main passageway, and a float-valve controlling the connection between said water-chamber and said auxiliary chamber.

8. In a pump, a water-chamber, an auxiliary chamber having inlet and outlet valves 10 said auxiliary chamber being connected with said water-chamber, an exhaust-port for said water-chamber, a compressed-air port for said water-chamber, pressure-means connected on one side with the auxiliary chamber, and on the other side connected with the interior of the water-chamber by a main and a restricted passageway, a valve structure operated by said pressure-means and controlling said exhaust and compressed-air 15 ports and said main passageway to close the exhaust-port, open the compressed air port, and open said main passageway in one direction and reverse the action in the opposite 20 direction.

9. In a pump, a water-chamber, an auxiliary chamber having inlet and outlet valves 25 said auxiliary chamber being connected with said water-chamber, an exhaust-port for said water-chamber, a compressed-air port for said water-chamber, pressure-means connected on one side with the auxiliary chamber, and on the other side connected with the interior of the water-chamber by a main and a restricted passageway, a valve structure 30 operated by said pressure-means and controlling said exhaust and compressed-air ports and said main passageway to close the exhaust-port, open the compressed air port and open said main passageway in one direction and reverse the action in the opposite 35 direction, and to open a relief on the first-named side of the pressure-means in the latter direction.

10. In a pump, a water-chamber, an auxiliary chamber having inlet and outlet valves 40 said auxiliary chamber being connected with said water-chamber, an exhaust-port for said water-chamber, a compressed-air port for said water-chamber, pressure-means connect- 45 ed on one side with the auxiliary chamber,

and on the other side connected with the interior of the water-chamber by a main and a restricted passageway, a valve structure operated by said pressure-means and controlling said exhaust and compressed-air 50 ports and said main passageway to close the exhaust-port, open the compressed air port, and open said main passageway in one direction and reverse the action in the opposite 55 direction, and a float-valve controlling the connection between the water chamber and said auxiliary chamber.

11. In a pump, a water-chamber, an auxiliary chamber having inlet and outlet valves 60 said auxiliary chamber being connected with said water-chamber, an exhaust-port for said water-chamber, a compressed-air port for said water-chamber, pressure-means connected on one side with the auxiliary chamber, and on the other side connected with the 65 interior of the water chamber by a main and a restricted passageway, a valve structure operated by said pressure-means and controlling said exhaust and compressed-air 70 ports and said main passageway, said valve structure being moved by the latter portion 75 of the movement of said pressure-means.

12. In a pump, a water-chamber, an auxiliary chamber having inlet and outlet valves 80 said auxiliary chamber being connected with said water-chamber, an exhaust-port for said water-chamber, a compressed-air port for said water-chamber, pressure-means connected on one side with the auxiliary chamber, and on the other side connected with the 85 interior of the water-chamber by a main and a restricted passageway, a valve structure operated by said pressure-means and controlling said exhaust and compressed-air 90 ports and said main passageway, and a float-valve controlling the connection between said water-chamber and said auxiliary chamber, said float-valve being confined for 95 vertical movement in a cylinder through which water may pass.

In witness whereof, I hereunto subscribe my name this 15th day of September, A. D 1915.

BURTON S. AIKMAN
